(57) **CLAIM**

The ornamental design for a dog ramp, as shown and
described.

DESCRIPTION

FIG. 1 is a perspective view of a dog ramp showing the new
design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof; and

FIG. 8 is a bottom plan view thereof.

FIG. 9 is an enlarged view of the encircled portion in FIG.
1.

FIG. 10 is an enlarged view of the encircled portion in FIG.
1.

FIG. 11 is an enlarged view of the encircled portion in FIG.
2.

FIG. 12 is an enlarged view of the encircled portion in FIG.
2; and,

FIG. 13 is a perspective view of the dog ramp in a folded
position.

The equal-length broken lines depict portions of the dog
ramp that form no part of the claimed design.

The dash-dot lines in FIGS. 1, 2, 9, 10, 12, and 13 illustrate
the boundaries of the enlarged view indicators and form no
part of the claimed design.

1 Claim, 13 Drawing Sheets
